[57] ABSTRACT

In a tracked air cushion vehicle system, the vehicle is supported and/or guided by one or more air cushions formed in a chamber between a wall of the track and a support of guidance platform, the enclosure of the chamber being completed by walls or bogies linked to the platform but movable independent of it, at least in a direction towards and away from the track without having to move with the platform and thus bear loads imposed by it. Both pendulum and non-pendulum forms of suspension are described, and the preferred embodiments of the invention utilize air cushions operating at subatmospheric pressures.

AIR-CUSHION VEHICLES

This invention relates to air cushion vehicle systems and more especially, though not exclusively, to tracked systems employing subatmospheric pressures to form a suspension medium.

For a comprehensive review of the prior art relating to tracked air cushioned vehicles, reference is made to an article by the inventor entitled 'The Evolution of Tracked Air Cushion Vehicles' appearing on pages 17-48 of the Aug. 1970 and continued on pages 6-39 of the September 1970 issues of 'Hovering Craft and Hydrofoil' published by Kalerghi Publications, 51, Welbeck Street, London W.1. In respect of systems employing subatmospheric pressures, additional reference is made to British Patent Specification Nos. 1,167,621, and 1,193,856.

Presently proposed tracked air cushion vehicle systems suffer from two limitations which it is a principal object of the present invention to relieve although the invention also provides advantages in non-tracked systems.

When a tracked vehicle travels round a curve in its track, it requires a radial force proportional to the square of its velocity to maintain it on the required path, which force must be applied to the vehicle by the track, as must a force sufficient to sustain the weight of the vehicle. Unless the resultant of these two forces acts perpendicularly to the track, a residual force will act on the vehicle tending to move it laterally relative to the track. The reaction from the track resisting such lateral movement must be sustained by the suspension of the vehicle. By superelevating the track on curves it may be arranged that, for one specific vehicle speed, there is no component force acting laterally of the track, but this remains true only for this specific speed and cannot compensate for lateral forces arising from other reasons such as wind pressure. In any practical system, the degree of superelevation employed must in any event be a compromise, since it cannot be ensured that vehicles will at all times and in all circumstances travel at the speed for which the superelevation is designed. Moreover, the maximum practical degree of superelevation is limited by the necessity of ensuring stability of a slow moving or stationary vehicles on a curve end and of preventing excessive lateral forces being applied to the track, as well as by considerations of passenger comfort in a passenger vehicle.

One way of relieving the limitations caused by uncancelled lateral forces on the vehicle is to provide it with either a primary or a secondary pendulum suspension. By a primary suspension is meant apparatus by which the vehicle is guided on or in the track, whilst by secondary suspension is meant apparatus connecting the load carrying portion of the vehicle with the primary suspension. A pendulum secondary suspension does not alter the point of application of the lateral loadings applied to the track by the vehicle primary suspension, although it may increase vehicle stability and improve passenger comfort. A pendulum primary suspension has the disadvantage that once the pendulum movement permitted is sufficient to have a significant effect on vehicle performance, it becomes impossible in known systems to apply any appreciable damping on rolling movement of the vehicle relative to the track.

In a tracked air cushion vehicle, the primary suspension is provided by an air cushion, or in practical sys-

tems, a plurality of air cushions, maintained between the vehicle and an elongated track surface or surfaces, which may be of various cross sectional configurations. In one class of configurations the track surface is part 5 cylindrical, so that the vehicle may roll laterally without constraint due to interaction between the track surface and the vehicle. A vehicle for such a system must obviously have a centre of gravity below the centre of curvature of the track, unless some auxiliary means is provided to keep it upright, and the primary suspension will provide no roll stability, nor can such stabilization be provided except by auxiliary support means.

All existing practical embodiments belong to the second class in which movement of that part of the vehicle 15 defining the air cushions relative to the track is strictly limited. This overcomes the roll stability problem, but reintroduces the problem of sustaining lateral loads in the primary suspension; moreover, the relative movement possible between the cushion defining apparatus 20 and the track is so limited for practical reasons that a secondary suspension is more or less essential and may need to be of considerable complexity.

In a tracked air cushion vehicle, the sustaining of lateral loads in the primary suspension is complicated 25 since the air cushion systems used for this purpose will in practical systems have to operate under widely varying loadings which may be in either lateral direction, as opposed to the cushions used to sustain the weight of the vehicle, on which the loading will always be in the 30 same direction and will not vary widely during operation. The problem is aggravated by the necessity of keeping the gaps between the edges of the means defining the cushions and the track to a minimum.

This same necessity for keeping air gaps to a minimum 35 leads to a second principal limitation of existing tracked air cushion vehicle systems. Assuming the means on the vehicle confining a particular air cushion to have a surrounding wall or skirt that behaves as if it is essentially rigid (flexible skirts are held rigid during operation by the air pressure acting on them), the degree of curvature of the track surface over which the cushions run which can be permitted before air leakage between the track and the skirt becomes excessive is strictly limited, the permissible curvature decreasing as the cushion increases in size. On the other hand, if the cushion is to be effective in its role of defining the position of the vehicle relative to the track as well as sustaining the loads applied by the vehicle to the track 40 without excessive contact therewith, its surrounding skirt must have a fairly high effective rigidity. A similar problem arises with untracked systems where the capability of the vehicle skirt to conform with a supporting surface is limited by the effective rigidity of the skirt, and the vertical primary suspension movement is limited.

This limitation results in the necessity for providing 45 large vehicles required to traverse appreciable horizontal and/or vertical curvature with a number of independent suspension 'bogies' which must be connected to the remainder of the vehicle by a secondary suspension of considerable complexity.

A further connected difficulty arises where the vehicle 50 is to be propelled by a linear induction motor, henceforward abbreviated LIM, or other means of propulsion in which accurate registration between interaction components on vehicle and track is required and which is not self registering as for example a wheel

would be. This accuracy of registration further limits the movement relative to the track permissible in the vehicle primary suspension if this used to control the registration, and in doing so aggravates the problem of allowing for track curvature to such an extent that separate means are usually provided to control registration.

A principal object of the invention is to provide a tracked air cushion vehicle which enables the above limitations to be overcome.

According to the invention, there is provided an air cushioned vehicle system, including a vehicle comprising at least one air cushioned support or guidance means comprising a first wall facing a surface upon which an air cushion may be sustained, and further walls cooperating with the first wall and with the surface to define a chamber, means on the vehicle communicating with the chamber to maintain therein a pressure differing from the surrounding atmosphere whereby to apply a supporting or guiding force to the first wall, which first wall is connected to or forms part of a load bearing portion of the vehicle, wherein the first wall is guided by the further walls for movement relative both to the sustaining surface and to the further walls at least in a direction towards and away from the sustaining surface, the further walls being located relative to the sustaining surface in this direction by interaction with the sustaining surface and wherein the pressure within the chamber is controlled in response to movement of the first wall relative to the sustaining surface.

Preferably the sustaining surface is the surface of a track configurated both to guide and support the vehicle. Preferably also such a track is of an inverted channel section, the first wall being an elongated support platform from which a load bearing vehicle body is suspended, and the further walls are provided by end members extending to the roof and side walls of the track and linked to the end of the support platform, the end members being restrained against substantial transverse or vertical movement relative to the track.

The essential difference between the above system and known air cushion vehicle systems is that the load bearing function of the air cushion defined by the chamber is largely isolated from the function of locating the suspended vehicle relative to the sustaining surface in at least one dimension. With conventional air cushions, the skirt or side walls of the cushion interact with the track and being rigidly connected with that wall of the chamber in which the cushion is formed, which sustains the loadings applied by the vehicle to the cushion, the skirt or side walls locate the vehicle because as any movement of the vehicle must be transmitted to them, leading to considerable movement of the skirt or side walls, relative to the track and consequent difficulty in maintaining a suitable air gap. It is true of course that conventional skirts are made of flexible material, but the function of this flexibility is to only permit local deformation to accommodate irregularities in the surface with which the skirt interacts, and regarding the cushion as a whole, the skirt behaves as if it were essentially rigid, the clearance between the facing wall of the cushion chamber and the sustaining surface being determined by the instantaneous pressure in the chamber and the load on the cushion.

Since in the present invention the wall of the chamber facing the supporting surface is free to move at

least towards and away from that surface independently of the further walls defining the chamber enclosing the air cushion, there is no theoretical necessity for forces in that direction to be transmitted to those other walls, although it may be convenient or practically necessary to provide some such force transmission to achieve damping of the movement of the vehicle. The resultant reduction of loading on the further walls makes it much easier to operate the latter with small air

10 gaps between them and the sustaining surface, and the ability of these walls to move independently of the first wall facing the sustaining surface means that they can be designed to be able to conform to track curvature in a tracked system whilst retaining a rigid first wall.

15 It should be clearly understood that the air cushions referred to above may be operated at either superatmospheric or subatmospheric pressures; in the first case, the force applied to the vehicle will tend to force the latter away from the track surface, and in the second case will draw it towards the sustaining surface. It should also be understood that the loading sustained by the cushion may be either or both a sustaining force supporting the weight of the vehicle, or, in a tracked system, a guiding force maintaining the vehicle on its correct path. A complete air cushion suspension system for a tracked air cushion vehicle system must include a cushion or combination of cushions fulfilling both functions, and these cushions may operate at either sub- or superatmospheric pressures or some at one and some at the other.

It will have been noted that the first walls of the air cushion chamber other than the wall facing the sustaining surface do not define the location of the latter wall relative to the sustaining surface at least in the dimensions in which it has freedom of movement relative to the sustaining surface and it is therefore necessary to provide independent means to ensure that the location of the first wall is stabilized.

20 This is achieved very easily by utilizing the movement of the first wall relative to the sustaining surface to control the pressure in the air cushion chamber and thus increase or decrease the force applied to the first wall by the air cushion so as to stabilize the location of the wall. Various methods of control are available.

25 Where in a tracked system the first wall is an elongated support platform itself having at least one edge adjacent the track surface, the latter may be profiled so that movement of the platform causes variation of the gap between said edge and the surface, providing the desired regulating effect.

30 In another arrangement, a sensor is provided to determine the distance between the first platform and the track surface, the signal from the sensor controlling the admission and/or exhaust of air from the chamber.

35 However, where the further walls of the chamber, are end plates or bogies located by the track, it is preferred in many instances to utilize the relative movement of the end plates or bogies and the platform to control the air pressure in the chamber. In one arrangement, the movement of the platform uncovers to a greater or lesser extent ports formed in one or more of the end plates or bogies, whilst in another arrangement, a control signal is generated which controls the exhaust and/or admission of air to the chamber.

40 Since in each case the movement of the first wall is independent of the further walls in at least one direction, extended movement of the facing first wall in this

dimension may be permitted as compared to arrangements in which no such relative movement is possible, thus enabling difficulties in known systems due to limited primary suspension movement to be overcome.

Moreover, by giving the first wall freedom to tilt about the axis of progression of the vehicle as well as the freedom to move towards and away from the sustaining surface, a pendulum primary suspension may be provided, with its attendant advantages, in which the necessary damping of the pendulum movement can be provided by applying damping between the first and further walls, bearing in mind that the latter are located relative to the sustaining surface.

It will be appreciated that the further walls must be positively located relative to the track, either by means of air cushions or fluid bearings or other means such as wheels. However, these walls will not be required to bear the forces needed to sustain the weight of or to guide the remainder of the vehicle, except for forces applied through any dampers provided between said walls and the first wall. Therefore, the problem of adequate guidance of the further walls is greatly eased.

Where the air cushion enclosed by the chamber is the or one of the main supporting cushions for the vehicle, it is normally most convenient that, assuming a tracked system using subatmospheric pressures, the track is of inverted channel section, providing the top and side walls of the chamber, the first wall being a suspension platform from which the remainder of the vehicle is suspended forming the bottom wall of the chamber, and the end walls being provided by end plates or bogies located by the cross section of the track and closing the ends of the chamber. The weight of the vehicle, except in most cases for the end plates or bogies, is sustained by a subatmospheric pressure maintained in the chamber by means on the vehicle and acting on the platform wall, whilst the end plates or bogies are linked to the platform by means allowing relative movement at least in the up and down direction. If LIM's are used for propulsion, these are advantageously located in end bogies so as to take advantage of the accurate location of the latter relative to the track.

Since the end walls or bogies need only be short compared with the length of the air cushion, they can negotiate bends in the track without difficulty.

If the linkage between the end plates or bogies and the bottom wall of the chamber is designed to allow pivotal as well as up and down motion, the same cushion may be utilized to provide lateral guidance as well as support of the vehicle, since the pendulum movement of the platform then permitted allows the latter to assume a position in which the resultant of the supporting and guiding forces is in line with the resultant of the forces applied to the platform by the air cushion.

If the linkage between the end bogies or plates and the first wall is designed to allow lateral as well as vertical movement, and the platform comprises a vehicle support member together with at least two pairs of vertically separated longitudinally extending horizontal walls located laterally by the side walls of the inverted channel section track so as to enclose, together with the support member and the end bogies, at least two further chambers between the support member and the track side walls, operation of these chambers at sub- or superatmospheric pressure will permit guidance forces to be applied to the vehicle.

Further aspects of the invention will be discussed below with reference to the accompanying drawings in which:

FIG. 1 shows a vertical longitudinal cross section through part of a system according to one embodiment of the invention, on the line I — I in FIG. 3,

FIG. 2 shows a horizontal cross-section of the same embodiment on the line II — II in FIG. 4.

FIG. 3 shows a vertical transverse cross-section on the line III — III in FIG. 1,

FIG. 4 shows a vertical transverse cross section on the line IV — IV in FIG. 2,

FIGS. 5, 6, 7 show alternative forms of track cross-section on an enlarged scale,

FIG. 8 illustrates graphically the effect of differing track profiles.

FIG. 9 diagrammatically illustrates a further form of track profile.

FIG. 10 diagrammatically illustrates the inner end of one form of end bogie,

FIG. 11 is a detail on an enlarged scale of the same end plate,

FIG. 12 is a cross section on the line XII — XII in FIG. 11,

FIG. 13 is a diagrammatic view of one damping arrangement for the embodiment of FIGS. 1 — 4,

FIG. 14 is a longitudinal vertical cross section of a second main embodiment of the invention on the line XIV — XIV in FIG. 15,

FIG. 15 is a longitudinal horizontal cross section of the same embodiment, on the line XV — XV in FIG. 14,

FIG. 16 is a vertical lateral cross section on the line XVI — XVI in FIG. 14,

FIG. 17 is a vertical lateral cross section on the line XVII — XVII in FIG. 15,

FIG. 18 is a detail on an enlarged scale showing an end bogie inner end plate and associated parts,

FIG. 19 is a section on the line XIX — XIX in FIG. 18,

FIG. 20 is a graphical illustration of the effect of different configurations of ports in the bogie inner end plates,

FIG. 21 is a vertical lateral cross section through a further embodiment of the invention, on a straight track section,

FIG. 22 is a similar section through a curved track section of the same embodiment,

FIG. 23 is a sectional detail through a straight track section the same embodiment of FIG. 21 the line XXIII — XXIII in FIG. 27 showing an end bogie inner end plate and associated parts,

FIG. 24 is a sectional detail on the line XXIV — XXIV in FIG. 27,

FIG. 25 is a sectional detail of a curved track section of the same embodiment, otherwise corresponding to FIG. 23,

FIG. 26 is a simplified version of FIG. 25 showing the support platform in its emergency landing position,

FIG. 27 is a longitudinal section through the bogie end plate in the condition shown in FIGS. 23 and 24,

FIG. 28 is a section through track and support member of a vehicle of a further embodiment of the invention, on the line XXVIII — XXVIII in FIG. 29,

FIG. 29 is a longitudinal horizontal section on the line XXIX — XXIX in FIG. 28, showing half the vehi-

cle support member, with its centre and end plates omitted for the sake of clarity,

FIG. 30 is a longitudinal vertical section on the line XXX — XXX in FIG. 29, showing half the vehicle support member,

FIG. 31 is a side elevation of one half of the vehicle support member with the center and end plates again omitted,

FIG. 32 is a plan view of one half of the vehicle support member with the center and end plates omitted,

FIG. 33 is a section through the vehicle support member on the line XXXIII — XXXIII in FIG. 30,

FIG. 34 is a transverse section showing the construction of an end plate,

FIG. 35 is a section on the line XXXV — XXXV in FIG. 30,

FIG. 36 is a corresponding section with the platform rounding a severe bend in the track,

FIG. 37 is a section on the line XXXVII — XXXVIII in FIG. 30

FIGS. 38 and 39 are sections on the lines XXXVIII — XXXVIII and XXXIX — XXXIX in FIGS. 34 and 37 respectively,

FIG. 40 is a horizontal half section through a further embodiment of the invention, showing the lateral guidance arrangement,

FIGS. 41 and 42 show diagrammatically two types of edge configuration for the support platform of the embodiment of FIGS. 1 — 4,

FIGS. 43, 44, 45 and 46, 47 show diagrammatically sections and details of further types of support platform,

FIGS. 48 — 50 show in section various forms of sliding edge seal suitable for use with those embodiments of the invention using such seals,

FIG. 51 is a diagram illustrating the problem imposed by track curvature in providing seals at the edges of the support platform,

FIGS. 52 and 53 show in vertical section and in plan diagrammatic view of a further form of conformable edge seal,

FIGS. 54A, B and C illustrate diagrammatically the mounting of conformable edgeseals on a support platform,

FIGS. 55a and b illustrates diagrammatically a vertical transverse cross section of a further embodiment of the invention,

FIGS. 56, 57 and 58, show details of a variant of the embodiment of FIGS. 55a and b,

FIGS. 59, 60A and 60B, 61 and 62 illustrate diagrammatically further features and developments of the embodiment of FIGS. 55a and b,

FIG. 63 illustrates diagrammatically in vertical transverse section yet a further embodiment of the invention,

FIGS. 64 and 65 illustrate the behaviour of the embodiment of FIG. 63 under the action of lateral force,

FIGS. 66A and 66B show fragmentary elevational and plan views of the embodiment of FIG. 63,

FIGS. 67 and 68 show details in lateral vertical section of variants of the embodiment of FIG. 63,

FIGS. 69 — 73 show in diagrammatic cross section the altitudes assumed by the principal parts of a further embodiment of the invention under various conditions,

FIGS. 74A, B and C illustrate the effect on the embodiment of FIGS. 69 — 73 of pitching motions, and

FIGS. 75A, B and C illustrate the effect of yawing motions on the same embodiment.

Referring to FIGS. 1 — 4, an elevated double track 2 is provided, comprising a central beam 4 supported at intervals by pillars 6. The underside of cantilever extensions from the central beam provide an inverted support surface 10 within each of two inverted channel section tracks 8a and 8b, guidance surfaces 30 being provided by the inner surfaces of depending walls 12.

It should be understood that so long as these support and guidance surfaces are provided, the structures providing these are sufficiently strong, and sufficient clearance is provided for vehicle bodies 14, the precise form of construction of the structures providing the surfaces is immaterial and will be dictated by convenience, and economic, aerodynamic and aesthetic considerations. In this connection however, attention is drawn in this and later embodiments in which a section of the track section as a whole is shown, to the function of the central beam and any downward extension thereof, not only in supporting the tracks but also in providing aerodynamic isolation between vehicles on opposite tracks, and creating a sheltered location for the vehicles in which they will be less influenced by wind.

The vehicle bodies 14 are each suspended from the track by means of a support truck 16, captive within the track section so that the vehicle bodies are always supported even when the support truck has no air cushion support. The design of the vehicle bodies forms no direct part of the invention and may be adapted to suit the purpose of the vehicle, usually the carriage of passengers.

The body 14 is connected to a suspension platform 20 by means of columns 18, the suspension platform 20 together with end bogies 22 forming the support truck 16. The suspension platform comprises a tubular beam 24 with laterally extending wings 26, the upper surface of the beam and wings forming the bottom wall of a suction chamber 28, the top wall of which is provided by the surface 10, whilst the side walls are provided by the inner surfaces 30 of the walls 12, and the end walls by the inner end plates 54 of the end bogies 22. Apertures 32 are provided in the top wall of the beam 24.

The ends of the tubular beam 24 are connected by flexible air hoses 78 to extraction fan units 34 mounted in the end bogies so that, when the fan units 34 are running, air is extracted from the chamber 28 through the apertures 32.

The end bogies themselves are guided and supported respectively by air cushions trapped by air curtains 36 issuing from beneath walls 50 and acting on the surfaces 30, the cushions being operated at positive pressure, for example by air extracted by the fan units 34 and supplied to plenum chambers 52, and by negative pressure air cushions generated chambers 38 defined by suspension plates 40 connected by ducts 42 to the extraction fan units 34, the suspension plates being provided with end skirts 44 and cooperating with dovetail section sub-tracks defined within the tracks 8a, 8b by longitudinal extending projections 46, 48. These systems of air cushions leave the end bogies free to move longitudinally along the track, but severely limit the extent to which they can move in any other direction, the end bogies thus being accurately located relatively to the track. In an alternative arrangement, the end bogies may be located in the track by means of wheels. They may in any event be equipped with wheels to support

the bogie, and preferably the entire vehicle, when the various air cushions are not operating.

The bogies will further comprise a body supporting the parts already mentioned, comprising an inner end wall 54, a bottom wall 56 and an outer end wall 58.

The projection 48 carries a longitudinally extending metallic reaction plate 47 which depends between windings 60 of a LIM mounted on each of the end bogies. Due to the accurate guidance of the end bogies, only a relatively small clearance is required between the plate and the windings, and a relatively high efficiency is possible.

The end bogies are linked to the suspension platform 20 in a manner which is discussed further below, but which allows the platform to execute both rocking movements relative to the bogies and movements perpendicular to the upper surface of the platform. As previously mentioned, the chamber 28 enclosed between the track surface 10 and the facing wall provided by the suspension platform 20 is maintained at subatmospheric pressure, the pressure drop being sufficiently great relative to the area of the platform 20 to lift the latter and the vehicle body and load which it supports. Assuming a predetermined capacity for the extraction fan unit 34, the platform will lift until the leakage of air between the side edges of the platform 20 and the walls 30 balances the capacity of the fan unit, the angle of the walls 30 having the effect that a much larger vertical movement is required for a given change in air flow through the gaps between the platform and walls than is the case with known systems, thus permitting much greater primary suspension movements than are practicable in such known tracked air cushion vehicle systems. This reduces or avoids the necessity for a secondary suspension system, and in the presently described embodiment no such secondary suspension system is in fact provided, though such a suspension could of course be provided if desired.

By changing the profile of the walls 30, differing suspension characteristics can be imparted to the vehicle; thus FIGS. 5, 6, 7, 8 and 9 show alternative profiles for the walls 30. FIG. 8 includes a graph illustrating the relationship between lift force and vertical position for the four profiles A to D illustrated in that Figure. It should be understood that the profiles in FIG. 8 are for the purpose of illustrating the effect of different profile features, and it is not suggested for example that profile C represents a practicable profile as it stands.

Referring to FIG. 9, here the surfaces 30 are formed with lower arcuate portions 61 having the centres of their arcs at the lower extremities of the inclined straight portions 62 of the opposite wall. The arcs are of a radius equal to the distance between the walls at their lower extremities (which equals the width of the platform 20 plus twice the air gap between it and the wall portions 61 when it has both edges adjacent the latter, with this arrangement the platform will tend to rotate about an outer edge as shown by the intersection of lines B, C and E. Thus, with this configuration the platform 20 will be confined to the region between the straight inclined wall portions 62 during straight running (line A—A normal weight, B—B maximum weight). During a turn of minimum radius when the effective load on the platform will be greatest, the suspension will be at its lowest limit and at its greatest angle of tilt, position C—C in FIG. 9. At lighter weight and minimum radius turn the platform will be at the

same angle of inclination but somewhat higher, D—D, with larger air gaps at the sides, while at maximum weight but in a larger radius turn the platform will be wholly in the circular arc section of the track but a reduced angle of inclination, E—E. In practice, curved surfaces on the walls would probably be avoided as the ideal curved surface is not likely to deviate far from a flat surface and flat walls are cheaper to manufacture.

Referring again to FIG. 7, it will be noted that on different sides of the figure, the track has been shown with sections of differing depth. This is because the maximum inclination of the platform 20 due to centrifugal forces on the vehicle is likely only to occur on tight bends, and in other locations a shallower track section will allow adequate clearance for movement of the platform.

The outline indicated by reference 64 is the locus of a locating pin 66 in the end of the beam 24 as a result of movement of the platform 20 within the track 8 (in each of FIGS. 5, 6 and 7 an extreme inclined position of the platform 20 is illustrated as well as an uninclined position in broken lines). The platform will assume such inclined positions in response to lateral forces acting on the vehicle, the inclination assumed by the platform being such that the horizontal component of the lift force due to the subatmospheric pressure in the chamber 36 acting on the platform 20 becomes equal and opposite to the lateral force.

FIG. 10 illustrates the end plate 54 of one end bogie 22, suitable as shown for use with yet another track profile although readily modified for use with any profile so far described. This end plate is formed with a guide slot 72 of shape corresponding to the locus 64 (see FIG. 7) of the centre of rotation of the platform 20, i.e. of the locating pin 66 on the end of the beam 24. The locating pin 66 is received by an elongated slot 80 in a bearing 70 sliding in the slot 72, movement of the platform 20 in a direction perpendicular to the locus 64 (see FIG. 7) being accommodated by this slot. Air sealing of the slot 72 is provided by a cover 74. The pin 66 (see FIG. 12) is retained by means of a flange 84 and washer 82.

In use, the embodiments so far described provide a suspension type tracked air cushion vehicle system with pendulum suspension and at the same time a substantial range of suspension movement perpendicular to the plane of the platform 20. Some means of damping rolling movement of vehicle body 14 and platform 20 relative to the track is desirable, and with the embodiment described damping may readily be applied by introducing friction between the bearing 70 and the pin 66 and/or plate 54, or by providing hydraulic dampers acting between the bearing 70 and some convenient point on the plate 54. Alternatively, the arrangement shown diagrammatically in FIG. 13 may be employed, in which auxiliary negative pressure air cushion assemblies 90 acting on the surface 10 outside the end bogies are carried by the roof of the vehicle body 14 via telescopic damper and spring combinations assemblies indicated generally as 92, thus applying damping forces to the vehicle. Additionally or alternatively, the end of the wings 26 of the platform 20 may be provided with pins engaging slots in the plates 54.

Whilst in this and the following embodiments, a vehicle body supported by a support truck comprising a single platform between two end bogies has been described, it will be understood that several such plat-

forms may be coupled together, or that an articulated train of alternate platforms and bogies may be provided. Each platform however will always have a bogie or equivalent structure at each end.

It will be noted in FIGS. 5-7 that a dihedral shape has been employed for the platform 20. It is believed that this contributes to lateral stability of the platform and helps to suppress hunting.

The embodiment so far described relies for regulation of the pressure in the chamber 28 upon gaps between the platform 20 and the surfaces 30. Whilst by changing the profile of the walls 30, the suspension characteristics of the vehicle can be altered as desired, it is economically desirable that the track profile be as simple as possible, and furthermore it is desirable for the sake of flexibility that vehicle suspension characteristics should be determined by the vehicle characteristics rather than the track characteristics since the latter obviously cannot readily be altered. The next embodiment to be described overcomes this difficulty, and also avoids a limitation upon the arrangement described above, in which the radius of curvature of the track which can be negotiated is limited by the necessity for providing sufficient clearance for the platform 20, which will normally be rigid, whilst at the same time avoiding excessive air gaps at the edge of the platform.

Referring to FIGS. 14-17, a double track 102 comprising a central beam 104 and supported by pillars 106 is provided as in the first embodiment. The track profile however is different, being a simple inverted channel section with a horizontal roof surface 110, and vertical side walls 112 providing guidance surfaces 130. A support truck for a vehicle 114 is prevented from escaping from the track by means of ledges 116. The support truck comprises a central tubular spine 118 extending between two end bogies 120. As will be described further below, the spine terminates in spindles 122 (see FIGS. 18 and 19) journaled in bogie end plates 124 in such a manner as to allow vertical and rotational movement relative thereto but not lateral movement. The tubular spine is connected by hoses 154 to air extraction units 126, and communicates through ports 128 with a chamber 140 enclosed by the surface 110, 130 of the track, the bogie end plates 124, and a support platform 132 carried by the spine 118. The support platform is provided with extensible conforming edge seals 134 (suitable seals are described further below) which may be longitudinally flexible or formed in hinged or separate sections so as to enable the edge seals 134 to conform closely with the surfaces 130. These edge seals are only required to reduce the air gap between the platform 132 and the surfaces 130 to small proportions and no load is placed on them in the plane of the upper surface of the platform 132 since the platform is located by the spine 118 and in any event is not subjected to forces acting in this plane. Consequently a very small air gap may be maintained without difficulty, thus greatly reducing the extraction unit capacity required to maintain the desired subatmospheric pressure in the chamber 140.

The end bogies 120 comprises bodies including the end plates 124, base plates 142, and outer end plates 144 providing a measure of streamlining. The body of each end bogie supports the windings 146 of a LIM, the rail 148 for which depends from the surface 110, as well as guidance and support air cushion units 150, 152 corresponding in function to the similar units provided

in the end bogies of the first embodiment; indeed, with the exception of the end plates 124 and associated parts in the present case, the bogies in each embodiment are very similar.

It will be appreciated that the conformable edge seals 130 of the platform 132 allow the latter to accommodate sharp curvature in the track without design compromises leading to excessive air losses from the chamber 140, whilst all the advantages of the first embodiment are maintained. A further advantage of the arrangement is that the connections between the spine 118 and the end plates 124 are simplified since only rotational and vertical movement need be accommodated.

Since there should be no change in air leakage between the edge seals 134 and the surfaces 130 as the platform 132 changes attitude, alternative arrangements must be made to stabilize the platform and control the suspension characteristics of the support unit. The means for achieving this is illustrated in FIGS. 18 and 19 which show a bogie end plate 124. The tubular spindle 122 terminating one end of the spine 118 passes through an elongated aperture 170 in the plate 124 and is retained therein by a collar 156, the spindle being journaled in a rectangular plate 158 guided for vertical movement by guides 160 carried by the plate 124. Thus vertical movement of the platform 132 is transmitted via the spine 118 to the plate 158. The plate has a downward projection 161, which progressively obturates the upper of two apertures 162 and 164 in the plate 124 as the platform 132 falls. The apertures communicate on one side with the interior of the bogie 120 of which the plate 124 forms a part, and on the other side via a chamber 166 and pipes 168 with the chamber 140. The apertures thus form an air bleed to the chamber. The aperture 164 is always unobturated and is designed to allow entry of enough air into the chamber 140 at all times to prevent any danger of the air extraction unit 126 stalling, particularly during starting. The aperture 162 will be obturated to a varying degree depending on the position of the plate 158.

It will be appreciated that the suspension characteristics of the platform 132 may be varied by altering this profile of the aperture 162 so as to alter the variation of air flow with changes in vertical position of the platform. A series 1-4 of possible profiles as illustrated in FIG. 20, together with a graph showing how the effective port area (i.e. capacity of air bleed) varies with displacement (i.e. vertical movement of the platform 132). The profiles shown are combined profiles for the apertures 162 and 164, the left hand portion of each profile representing the aperture 164.

Returning to FIGS. 18 and 19, damping of the platform 132 and hence the vehicle body 114 against roll is achieved by means of a system of cross connected hydraulic dampers. The collar 156, which rotates with the spindle 122, carries two oppositely extending lever arms 172 each connected to the pistons 182 of two oppositely acting hydraulic cylinders 174, the four cylinders being cross connected by pipes 176 and connected in parallel by a restrictor valve 178. The arrangement provides damping both of rotational and vertical movement of the platform 132, the rotational damping being controlled by the valve 178.

To prevent accidental contact of the plate 124 with the track, the air cushions supporting and guiding the

bogies 120 may be supplemented or replaced by wheels 180.

A variant of the embodiment of FIGS. 14-17 suitable for very high speeds is illustrated in FIGS. 21-27. The same reference numerals are used where applicable. Where high speeds are required round appreciable curves, substantial angles of inclination of the vehicle and its support platform may be involved. These angles provide problems since with the embodiment just described, the axis of the platform 132 must be maintained a substantial distance between the surface 110 so as to provide enough clearance above it to accommodate the maximum tilt of the platform. Although only sufficient accommodation for tilt to allow for wind resistance need be allowed for on straight track, the above clearance must still be allowed because the suspension of the vehicle is controlled by the vertical distance between axis of tilt of the platform 132 and the surface 110. Thus the sidewalls 112 of the track on straight stretches must be as deep as required for the sharpest curves, increasing costs and detracting from its appearance. In the embodiment to be described this problem is overcome by altering the vertical position of a plate containing the apertures 162 and 164 in accordance upon the tilt of the platform 132. FIG. 21 shows a section of the track on a straight section, and it will be seen that the walls 112 are quite shallow, whereas on a sharp curve (FIG. 22), very deep walls 122 are necessary to accommodate the tilted platform and the rotational axis of the platform 132 is at a very much lower level.

The spindle 122 is replaced by a square shaft 200 located by a slot 202 in a bearing carried by an assembly of upper and lower blocks 204 and 206 slidably mounted for movement up and down as slot 207 in plate 124, which is elongated downwards to accommodate the slot. Beneath the lower block 206 is a cross piece 208 carrying a box 210 in which the apertures 162 and 164 are formed. The upper block 204 supports a cross piece 212 carrying a pair of cylinders 214 having pistons spring biased towards each other. An horizontally movable actuating rod 216 has a pin engaging a slot 218 formed in a lever arm 234 extending upwardly from the shaft 200. Thus rotation of the shaft on tilting of the platform 132 (see FIG. 25) causes horizontal displacement of the rod 216 so as to displace inwardly the piston of one of the cylinders 214, forcing hydraulic fluid through interconnected pipes 226 into dual piston hydraulic cylinders 220, which have upper rods 222 connected to the upper edge of the plate 124 and lower rods 224 connected to the cross piece 208 consequently the latter, carrying the box 210, is forced downwardly. The box 210 is connected by flexible pipes to apertures (not shown) near the top of the plate 124 and opening into the chamber above the platform 132. The shaft 200 also carries a radiused plate 230 whose movement in response to vertical movement of the shaft 200 in the slot 202 provides variable obturation of the aperture 162, just as in the previous embodiment. However, movement of the platform 132 out of the horizontal results in downwards movement of the box 210, reducing obturation of the aperture 162 and thus admitting air to the space above the platform 132, causing the latter to descend until the plate 230 again sufficiently obturates the aperture 162. On the platform regaining a horizontal altitude, the reverse process takes place.

Other features of the embodiment of FIGS. 21-27 are that a simpler internal profile of the track section is achieved by using a single sided LIM with its reaction plate 232 (see FIG. 21) set into the surface 110. The vehicles 114 are provided with secondary suspensions comprising T shaped hangers 236 from the ends of the cross bars of which the vehicle bodies are suspended by pair of oppositely inclined links 238 (see FIG. 21). This arrangement permits the vehicle to accommodate lateral wind pressure from the direction of the arrow without the vehicle body being tilted (see the left hand side of FIG. 21), and reduces the maximum tilt of the body on curves (see FIG. 22), thus reducing the clearances required relative to the supporting structure of the track. Hydraulic or other actuators may be provided to assist the attitude change if necessary.

It should be appreciated that the slot 207 is provided with bellows type seals above and below the blocks 204, 206 to prevent air passing therethrough and auxiliary plates 125 associated with the plate 124 serve a similar purpose. FIG. 26 illustrates the attitude assumed by the support platform 132 should there be failure of the means for extracting air from the chamber 140 as a vehicle is rounding a bend. Rubbing strips 234 carried by the platform 132 engage the track ledges 116.

The platform 132 comprises extensible conformable edge seals 134 as in the previous embodiment, but in addition, the platform itself may be in several sections independently laterally movable upon sideways extending flanges 240 of the backbone member 118, in order to provide still further accommodation for track curvature. The sideways extent of these flanges 240 may be greater beneath the ends of the platform than in the centre (see the right and left hand sides respectively of FIG. 22) so as to provide clearance when the platform rounds a bend in the track, bearing in mind that the ends of the spine are located centrally between the walls of the track by the end bogies and thus its centre portion must be displaced towards the inside of the bend.

In the embodiments so far described, the vehicle or vehicles have been provided with a pendulum primary suspension. This has the advantage that the guidance and suspension forces are combined and are all sustained by the lift platform, thus overcoming the problem of sustaining widely varying lateral guidance forces independently of the suspension forces. However, the basic principle of the invention can also be applied to overcoming this problem in a non pendulum suspension by reason of its ability to isolate the functions of sustaining the guidance forces and defining the location of the vehicle within the track. The embodiment shown in FIGS. 28-39 illustrates a system in which a non pendulum primary suspension is employed. The vehicle body (not shown) is suspended by hangers (not shown) which may form part of a secondary pendulum suspension, from sockets 302 in a main frame member 300, of a lifting platform, sections of different parts of which are shown in FIGS. 28, 29, 30, 33, 35, 36, 37 and 38. The main frame member comprises generally box section end portions 304 defining chambers 306, multi-flange girder intermediate sections 308, and a box section linking portion 310. Coupling portions 312 extend beyond the end portions 304 and may be provided with couplings (not shown) to enable trains of vehicles to be coupled together. In the embodiment shown in the Fig-

ures which illustrate just over half of a suspension platform, two end portions 304 flank two girder sections 308 joined by a portion 310, though further sections 308 and portions 310 could be provided between the end portions 304 if desired.

The end portions 304 (see FIG. 28) have a width not substantially less than the internal width of the section of a track 314, which is of similar cross section to that used in the embodiment of FIGS. 14 - 17, whilst the intermediate sections 308 are of a substantially smaller width, thus allowing the frame member 300 to pass along a curved section of track without fouling the latter provided that the end portions 204 are properly located relative to the track. Carried by the flanges 307 of the girder sections 308 and end portions 304 of frame member 300 are a number of seal plates 334 and 336 movable horizontally relative thereto and cooperating therewith and with the track to divide the enclosed space between the member 300 and the track into three chambers 316, 318 and 320 to each side of the connecting section 310, the chambers 316 being defined between the top of the frame member 308 and the roof 322 of the track section, and being divided by a rail 324 depending from the roof 322 and forming part of a LIM propulsion system the coils of which (not shown) are carried by the end portions 304. The chambers 318 and 320 are formed between the vertical side walls of the portions 304 and 308 of the frame member 300 and the side walls 326 of the track. The chambers of each side of the connecting portion 310 are divided by a transverse divider plate 328 (see FIGS. 37 and 39) slidably mounted between the adjacent end walls 329 of the girder sections 308, and are closed at their outer ends by transverse end plates 330 (see FIGS. 34 and 38) slidably mounted against the outer end faces 331 (see FIGS. 29 - 33) of the end portions 304. The plates 328 and 330 being free to move both vertically and horizontally relative to the member 300 and are guided for accurately controlled movement along the track by fluid bearings 370 between the edges of the plates and the track and rail, and/or by wheels 332.

The seal plates 334 and 336 are arranged in groups of three, four groups of two plates 334 flanking one plate 336 being provided for the upper and lower flanges 307, respectively formed on each side of the girder sections and end portions of the member 300. The narrow outer ends of the plates 334, which are wedge shaped (see FIG. 32), are pivoted to the end portions 304 of the member 300 by pivots 338, whilst the plates 334 at their outer ends are pivoted to the plate 336 by pivots 340. A conformably edge seal 342 is provided along the outer edges of the combined sets of seal plates. The positions assumed by the seal plates as the platform rounds a bend in the track are shown in broken lines in FIG. 32.

The upper groups of seal plates 334 and 336 divide the chambers 316 from the chambers 318 and 320, the enclosure of the latter being completed by the lower groups of seal plates 334 and 336.

By means described further below, a controlled sub-atmospheric pressure is set up in each of the chambers 316, 318 and 320, and in the case of the chambers 316 this acts to provide a suspension force supporting the weight of the platform and the vehicle suspended therefrom, whilst the difference, if any, between the lateral forces exerted on the platform due to the depressions in the chambers 318 and 320 represents a lateral guid-

ance force. The member 300 from which the vehicle is suspended is free to move in response to any unbalance in these forces without imposing other than frictional loads on the various plates 328, 330, 334 and 336 with the same advantages as have been discussed in relation to previous embodiments.

It is of course necessary to provide means for stabilizing the location of the member 300 within the track, and this is achieved by arranging that movement of the end plates 330 controls the rate of admission of atmospheric air into the chambers 316, 318 and 320 in order to control the pressure therein. To this end each plate 330 carries on its outer (relative to the support platform) surface two box structures 352 each defining chambers 354 and 356 (see FIG. 34). The interior of the chambers 354 are placed in communication with the associated chamber 316 via flexible hoses 358 (see FIGS. 29-31), tubes 360 and orifices 362, and with the associated chamber 306 via orifices 364 and 366. The orifice 366 are more or less obturated by plates 368 (see FIG. 33 carried by the end portion 304, according to the vehicle position of that end of the member 300 relative to the plate 330 which lies against the end face 331 of the portion 304. The said vertical position is thus controlled in a similar manner to that described with reference to FIGS. 18 to 19. The suspension characteristics can be altered by changing the shape of the orifice 366, in a similar manner to that described with reference to FIG. 20.

30 The lateral forces applied to the member 300 are similarly controlled, the two chambers 356 (see FIG. 34) associated with each plate 330 being connected to the associated chambers 318 and 320 respectively by flexible hoses 372, pipes 374 and orifices 376 (see FIGS. 30, 31, and 34, and to the associated chamber 306 through orifices 378 (see FIG. 34) which are partially obturated by plates 380 (see FIG. 33) carried by the portions 304 of the member 300. The degree of obturation is controlled by the lateral position of the end portion 304 of the member 300 relative to the track and thus the member is subjected to a lateral guiding force proportional to its deviation from a desired mean position instead of its end portions with the movement of the spine member relative to the plate 328 being used to provide control of the lifting and guiding force coupled to the platform.

Since the two ends of the suspension platform have their vertical and lateral positions relative to the track independently stabilized by there interaction with the plates 330, yawing and pitching movements of the platform are automatically heavily damped, in a manner explained further with reference to FIGS. 74A, B and C and 75 A, B and C.

55 Air is withdrawn from the chambers 316, 318 and 320 by means of fan units 382, 384, 386 and 388 mounted within each of the sections 308 of the member 300, the fans exhausting along duct 390 into the associated chamber 306. The chamber 306 is vented to the atmosphere through an opening 392, and is fitted internally with sound deadening baffles 394. Since the air passing through the chambers 316, 318 and 320 is both drawn from and exhausted into the chambers 306, the opening 392 only serving to exhaust additional air introduced into the system by leakage past the various seals, the system is essentially a closed circuit one, and noise levels are very greatly reduced, an important factor in this type of transport system. Of the various fans,

which are driven by motors 412, the fans 382 withdraw air from the chambers 318 through ducts 396, the fans 384 withdraw air from the chambers 320 through ducts 398, and the fans 386 and 388 withdraw air from the chambers 318 through ducts 400 and 402 and orifices 404 and 406, the latter being exposed by cut-outs 408 in the plates 336. Further cutouts 410 in these plates provide for the wheels 332 and seals 370 of the centre plate 328.

Referring now to FIG. 40, this illustrates an alternative form of lateral guidance system that may be utilized in connection with a suspension system similar, in respect to the means used to control vertical movement of the platform, to that described in the previous embodiment. However, instead of chambers being defined to either side of a central spine 500 by means of two lower groups of sliding or conforming seal plates, two groups of positive pressure air cushion pads 502 are pivotally carried by the outer ends of a beam 504 pivoted in turn either to the spine 500 as shown or together with another similar beam carrying further pads, to the outer ends of a further beam itself pivoted to the spine 500. This arrangement enables lateral guidance to be provided together with excellent conformity to the track 506 on bends, since individual pads can be of very restricted length. The problem of designing the pads to accommodate widely varying lateral loads remains however.

Referring to the embodiments of FIGS. 1 - 13 and similar embodiments in which the air pressure within the chamber formed between the suspension platform and the track is regulated by variation of the gap between the lateral edges of the platform and the side walls of the track, FIGS. 41 - 47 show in section different configurations of the relevant parts of the platform P and the track T. In FIGS. 41 and 42, air is drawn through a simple gap G between the platform P and the track T. The capacity of a fan unit withdrawing air from above the platform is calculated to result in a width of the gap G which is a minimum compatible with the degree of irregularity permitted in the track wall and the extent of the suspension movements of the platform. In order to minimize damage due to occasional contact between the platform and the track wall, the platform edge E is preferably made of resiliently flexible material. This also helps in damping fluctuations in airflow through the gap G, as can give the edge E an upward inclination as in FIG. 42.

Greater efficiency can be achieved by directing a jet of air across the gap G. In FIG. 43, air is compressed by a compressor fan C and is conducted to the edges of the platform P, where it is ejected through nozzles N along the length of the edges to form air curtains A. If the nozzles N are directed downwardly away from the gap as shown in detail in FIG. 44, the air streams through the nozzles will induce a flow of air from the chamber B (see FIG. 43) above the platform generating a depression thereabove which partially or wholly supports the vehicle and thus wholly or partly replaces the necessity for a separate fan unit to withdraw air from this chamber. In creating the depression, the air curtains A will deflect as shown to meet the walls of the track T some distance from the actual gap G. The depression caused in the chamber will depend on the quantity of air expelled through the nozzles N, the velocity of ejection, and the angle of ejection. The arrangement is the converse of the air curtain method

used in conventional hovercraft for creating and sustaining an air cushion, and the principles of operation are similar.

The performance of the arrangement of FIG. 44 can be improved by providing a suction fan unit S to augment the depression set up in the chamber B, as shown in FIG. 45. In the detail to FIG. 45 it will be seen that a portion of the air curtain A is now drawn into the chamber B. In doing so, it is turned through a substantial angle and thereby acts as a throttle to the suction fan S.

Greater efficiency may be achieved using a recirculatory arrangement. In FIG. 46, a fan F withdraws air from the chamber B, thus setting up a depression therein, and after compressing the air, supplies it to the nozzles N to create the air curtains A. Either 100 percent recirculation may be employed in which case the air from the curtains A is wholly drawn through the gap G, as in the detail to FIG. 46, or the arrangement of FIG. 47 may be employed with a double sided fan D drawing air on one side from the chamber B and on the other side from the atmosphere.

The advantages of 100 percent or near to 100 percent recirculation are:

- a. that the power required to sustain the platform P (and the vehicle body it supports) is substantially only that required to compensate for frictional losses within the system,
- b. the power loss drag associated with the collection of ambient air, due to the need to accelerate the latter to the velocity of the vehicle, is eliminated,
- c. the possibility of ingesting into the fans foreign matter such as snow or airborne debris is reduced, and
- d. the external noise produced by the system is reduced.

Several embodiments of the invention described above make use of seals conforming to the track wall. In low speed systems, a simple sliding seal can be practicable as in FIG. 48, with a flexible sealing strip 1 pressed against a track wall T by means of springs 3 only one is shown received in a slot 5 in the edge of the platform P from which the sealing strip 1 protrudes. In a variant (see FIG. 49), the strip is connected to the wall of the slot 5 by means of a rolling diaphragm 7, substantially enclosing a channel 9 which is in communication with the atmosphere, the depression on one side of the seal drawing it into contact with the wall.

Such arrangements may be subject to heavy wear and introduce high frictional losses, and fluid bearing seals are preferred. Referring to FIG. 50, the arrangement of FIG. 48 is modified by the introduction of a recess 11 in the face of the strip 1 facing the wall T. This recess is connected by passages 13 and 15 to a pipe 17 carrying air under pressure, the pressurized air forming a fluid bearing beneath the sliding edge seal.

The embodiment of FIG. 50 can only provide a limited degree of conformity between a platform P with edges and curved track T, the problem being illustrated by the diagram of FIG. 51. To overcome this problem, the modification of FIGS. 52 and 53 may be employed, in which the slot 5 is formed in a channel assembly formed by a flexible rail 19 and plates 21. The rail 19 may be additionally supported relative to the wall of the track T by wheels 23. The rail is connected to the platform P by a bellows connection 25, and by struts 27 received in sockets 29 in the platform P and pressed outwardly by means of springs 31.

It should be noted that the sole function of all the above conforming edge seal arrangements is to form a seal between the atmosphere and an enclosed chamber, and they are not required to accept loading arising from the weight of the vehicle or the forces required to guide it which change with the attitude of the vehicle. Not only does this mean that the loadings that must be sustained by the seals are greatly reduced, but also the stability of the vehicle in the direction or directions controlled by the chamber enclosed is not necessarily directly affected by the conditions existing at the edge seal whereas this is always the case with conventional air cushion vehicles.

In the embodiment of FIGS. 28 to 39, an arrangement was described comprising a group of seal plates 334 and 336 and a flexible edge seal 342, the plates 334 being connected to the spine member 300 at their outer ends by the pivots to 338 the spine member 300 which was located laterally in the track by its end portions 304. Alternative arrangements for filling the same function are possible and are illustrated in FIGS. 54 A and C. FIG. 54 B illustrates diagrammatically the arrangement just described, the solid curved lines representing the innermost positions that can be assumed by the conformable edge seals 342 associated with groups of seal plates on opposite sides of the, the curved dotted lines the outermost positions of these seals during the traversal of curved track, and the straight connecting lines the positions of the end plates 330. The short straight lines between the curved lines indicate the position of the outer edges of the centre plate 328 when the platform is traversing straight track. In FIG. 54A, the pivotal connections X between the movable walls and the spine member are halfway along the latter, which in this embodiment is located in the track by its central portion instead of its end portions with the movement of the spine member relative to the plate 328 being used to provide control of the lifting and guiding forces coupled to the platform; the innermost and outermost positions that can be assumed by the conformable edge seals are denoted as before, with the short straight lines showing the positions of the outer edges of the end plates 330 when traversing straight track. In FIG. 54, a variant is shown in which the conformable edge seals are each pivoted to the spine member of the platform at two points X intermediate their length.

The embodiments of the invention which have been described as far all make use primarily of support and guidance air cushions operating under negative pressure. This is because such a system enables the use of a track of inverted channel section; such a track possesses very considerable advantages over non inverted track configurations in that it is not liable to capture foreign bodies or become clogged by snow. With a non-inverted track configuration, the risk of the track being rendered unusable under snowy conditions is high, and great hazards are presented by the presence of obstacles on or in the track, whether arriving there by malice or accident.

However, there is no reason why the principles of the invention should not be applied to systems utilizing positive pressure air cushions and such a system may be exemplified by the embodiment of FIGS. 28 - 39, if all the figures are considered as inverted and the direction of all air flows as reversed.

A further possibility is illustrated diagrammatically by the embodiment of FIGS. 55a and 55b, in which a chamber enclosed between a platform and the track may operate at positive or negative pressure at different times. A platform 600 connected to a vehicle bodies (not shown), is provided with track guided end bogies similar to those already described for example with reference to FIGS. 1 - 4, the platform and end bogies cooperating with a track 604 to enclose a chamber 602. The side walls of the track have divergent upper portions 606 and convergent lower portions 608, relative to the wall 624 of the track. When subjected to a downward force, the platform 600 tends to move downward between the convergent portions walls 608, and when subjected to an upward force, to move upwards between the divergent walls portions 606. The longitudinal edges of the platform are provided with nozzles 610 fed with air from a double sided centrifugal fan 612 driven by a motor 640 through gearing 642 (see FIG. 61) so as to provide air curtains 614. The fan has inlets on either side of the platform 600, and is equipped with a valve comprising plates 616, 618 connected by a shaft or shafts 620, the valve being biased by springs 634, 636 (see FIG. 61) so that the plate 618 normally closes the lower fan inlet, resulting in the fan drawing air from the interior of the chamber 602. The platform under these conditions operates so that the platform cooperates with the wall portions 608, in a similar manner to the embodiment of FIGS. 1 - 4. Should the platform be subjected to an upward force, the platform will rise until an actuator 622, which may be an auxiliary air cushion device (see FIG. 61) to which air is supplied by a fan 635, contacts the roof 624 of the track, thus actuating the valve, and causing the plate 616 to close the upper fan inlet whilst the plate 618 opens the lower fan inlet (see FIG. 55b).

The chamber 602 now receives air from the curtains 614 and operates at positive pressure, thus forcing the platform away from the wall 624 and limiting its upward movement. Unfortunately the alignment of the walls 606 tends to divert the air away from entering the chamber 602, and unfortunately also, the angle of the walls 608 tends to divert air into the chamber 602 when the chamber is operated at negative pressure, thus reducing the efficiency of the arrangement.

FIGS. 56 - 58 illustrate a configuration for the nozzles 610 designed to overcome this problem; in the nozzle 610 is placed a movable diverter member 624 which may be moved so as to cause the air passing through the nozzle 610 to pass to one side or the other of it, thus enabling the air curtain 614 to be diverted upwardly or downwardly as desired. One method of actuating the member 624 is illustrated in FIG. 59 on which the member is pivoted in a pin 626 and controlled by a linkage 628 which may be operated by the valve controlling the fan outlets (see FIGS. 61A and B), by means of cam plates 632 attached to the plate 618 and acting on the linkage 628 through roller followers 630, so as to cause upward diversion of the air curtains during positive pressure operation and downward diversion of the air curtains during negative pressure operation.

The arrangement just described, in which both positive and negative pressures may be applied to the chamber 602, is particularly useful in applying lateral restraint to a vehicle, since the force required to be applied to the vehicle may be in either direction. FIG. 63

is a diagrammatic cross section of a system operating on this principle. Although much simplified for the purposes of illustration, the system is basically similar to that of FIGS. 1 - 4, with a vehicle body 700 pivotally suspended from a suspension platform 702, which together with end bogies (not shown) cooperates with a track 704 to enclose a chamber 706.

However, the vehicle body is also pivotally connected to a guidance platform 710, operating as just described with reference to the platform 600 except that it cooperates with a vertically orientated track defined by side walls 712 to define a chamber 714. It is arranged that the normal line of action of the forces applied to the vehicle by the platform 710 should pass as near as possible through the aerodynamic centre 716 of the vehicle. This position is likely to vary according to operating conditions, but any residual aerodynamic forces acting on the vehicle will be counteracted by rotation of the vehicle as shown in the sketches of FIGS. 64 and 65 according to the direction of the force other lateral forces are accommodated in the same way.

In the embodiment, the platform 710 may be longitudinally displaced relative to the platform 702 in order to optimize its guidance function; in the previous embodiments described, lateral guidance forces have been applied to the platform having the same longitudinal distribution as the supporting forces. At high speeds however considerable lateral forces may be developed acting through points near the leading end of the vehicle. As shown in FIGS. 66A and 66B, it is advantageous under these circumstances to displace the guidance platform 710 so that the lateral forces it generates act through a point 718 near the leading end of the vehicle 700. In practice, a platform 710 is provided at each end of the vehicle to allow reversible working and also to damp out yawing movements of the vehicle.

It will be apparent from reference to FIG. 67 which shows a platform 710 equipped with a fan 720 that the embodiment just described is subject to the disadvantage that the lower of the two side walls 712 is liable to obstruction by snow, rain water or debris. This problem may be overcome as illustrated in FIG. 68, in which the lower side wall 712 is replaced by an inverted sidewall 722, and the platform 710 is provided with a retroverted edge portion 724 to interact with the side wall 722. The action of the arrangement is the same as before so far as the creation of lateral stabilizing forces is concerned, but the wall 722 is not subject to obstruction.

FIG. 62 illustrates a method, applicable to any of the embodiments of the invention other than those with 100 percent air recirculation, in order to increase the efficiency of the fan unit or units used. There is shown diagrammatically a support platform 51 between end bogies 53, the platform being equipped with an extraction fan 55 exhausting into a duct 57 which provides the secondary air of an ejector pump 61 whose primary air supply is provided by the velocity of the platform relative to the track and hence the ambient air.

FIGS. 69 to 75 illustrate the operation of a further embodiments of the invention having two suspension platforms in parallel (FIGS. 69 to 73) or series (FIGS. 74 and 75). In the embodiments so far described, a single suspension platform has generally been utilized enclosing with the track and associated end plates or bo-

gies a single chamber generating the force required to sustain the weight of the vehicle. However, the embodiment of FIGS. 28 - 39 employs two separate chambers 316 in series, and this principle may be extended to other embodiments of the invention as illustrated diagrammatically in FIGS. 74A, B and C which shows a longitudinal cross section and two spaced transverse cross sections of a vehicle and track in order to control pitching of the vehicle by increasing the pitch stiffness of the primary suspension. It will be seen that two platforms 800, 810 define, with the cooperation of a track 802, end plates 804 and a centre plate 806, two chambers 808 and 812 in which the platforms 800 and 812 can move independently in the vertical direction, such independent movement creating differential lift forces on the two ends of the vehicle 814 tending to damp out pitching movements.

The same arrangement is effective in damping out yawing motions, as is illustrated by FIGS. 75A, B and C. FIGS. 75A shows the vehicle 814 in plan, and the nature of the yawing movement giving rise to the platform altitudes is shown in FIGS. 75B and 75C which are transverse cross sections corresponding FIGS. 74B and 74C. It will be understood that the assumption of these attitudes by the platforms 800 and 810 will give rise to lateral forces on the ends of the vehicle producing a couple resisting the yawing motion.

Instead of or additionally to providing series pairs of support platforms, parallel pairs of platforms 900, 910 may be provided, as in FIGS. 69 and 70, running in parallel tracks 902, 904. This enables rolling of vehicle 914 to be damped. The vehicle 914 is supported from the platforms by sets of swinging links 906, 908. Pure roll of the vehicle is resisted by a restoring couple set up by differential vertical displacement of the platforms as shown in FIG. 69. The application of side loads to the vehicle, due for example to wind, is resisted by inclination of the platforms as shown in FIG. 70, again producing a restoring force, although in this case the vehicle remains level. The behaviour of the vehicle in roll and under the application of side loads may readily be modified by altering the points of attachment of the links 906, 908 to the vehicle 914, as shown in FIGS. 71 and 72. The tracks 902, 904 may be placed at different levels on bends as shown in FIG. 73, so as to provide the same effect as superelevation of a single track.

In all the embodiments in which the means of propulsion has been specified, this has been a LIM. It will of course be understood that some means must be provided for transferring electrical energy to the LIM windings on the vehicle, and to the motors driving the various fans employed. Conveniently, the end plates or bogies of the suspension truck or trucks, platform or platforms, are provided with collection shoes or pantographs contacting conductors running either along the inside surface of the track section or at some convenient location adjacent the open side of the track section.

It should also be understood that other means of propulsion may be employed, for example, a propellor driven by any suitable form of engine or motor, a jet engine, or driving wheels acting on the track.

Further, whilst the invention is expected to find its primary utility in the transport of passengers, systems according to the invention may also be employed for the carriage of freight. A difficulty with existing sys-

tems where freight carriage is concerned is that the gross weight of a freight vehicle will vary according to its loading over a very wide range compared with that of a passenger vehicle, leading to severe difficulties in providing an air cushion suspension system capable of operating satisfactorily throughout this range. In the present invention, the improved range of suspension movement which can be achieved, together with the fact that at least in certain embodiments the suspension characteristics of a lift platform may readily be altered by means of altering the shape of an obturable aperture, enables these problems to be overcome. It is anticipated that a freight vehicle need comprise no more than a conventional container spreader suspended from a lift platform as described in connection with any of the described embodiments of the invention has been specifically described above with reference to its application to tracked guided vehicle systems in which it is expected to find its primary utility. However, the invention can also be applied to free air cushion vehicle systems, the track being replaced by a sustaining surface having no guidance function. In a typical case, such a system would involve the use on a suitable surface of a vehicle comprising a platform, a skirt surrounding the platform, and means such as a fan generating a superatmospheric pressure within the chamber enclosed by the platform, the skirt and the supporting surface, as in a conventional air cushion vehicle, the platform being however free to move vertically relative to the skirt thus enabling the platform to have a range of vertical suspension movement independent of the skirt characteristics. As in the tracked embodiments, the pressure within the chamber would be controlled in response to movement of the platform relative to the sustaining surface.

What I claim is:

1. An air cushion vehicle system including an elongated track of a channel section having a bight portion defining a vehicle sustaining surface, said system further including a vehicle having at least one air cushion means, said air cushion means comprising a first wall facing said surface and further walls at opposite ends of said first wall and cooperating with said first wall and with said channel to define a chamber, pressure control means on the vehicle communicating with said chamber to maintain therein a pressure different from the surrounding atmosphere whereby to apply a suspension force to said first wall which wall is associated with part of a load bearing portion of the vehicle wherein the first wall is guided by said further walls for movement relative both with respect to the sustaining surface and to said further walls at least in a direction towards and away from the sustaining surface, said further walls being located relative to said surface in said direction by interaction with the sustaining surface, and wherein the pressure within the chamber is controlled in response to movement of the first wall relative to the sustaining surface in said direction.

2. A system according to claim 1, wherein the track is configured both to guide and support the vehicle.

3. A system according to claim 2, wherein the track is inverted and said sustaining surface is the roof thereof.

4. A system according to claim 3, wherein the first wall is an elongated support platform from which a load bearing body of said vehicle is suspended, the further walls are provided by end members selected from

plates and bogies, said end members extending to the roof and side walls of the track and linked to the ends of the support platform, said end members being restrained against substantial transverse movement relative to the track.

5. A system according to claim 4, wherein the vehicle is propelled by at least one linear induction motor mounted in cooperating relation with an end member.

10 6. A system according to claim 4, wherein the connection to the end members is such as to allow both motion of the platform relative thereto in a vertical direction and tilting movement of the platform about a longitudinal roll axis thereof.

15 7. A system according to claim 6, characterized in that the platform is of predetermined width, and the side walls of the track have a cross-sectional profile selected to provide a predetermined relationship between the location of the platform within the track and the width of the gaps between the platform and the side walls.

20 8. A system according to claim 7, characterized in that the platform is provided with flexible longitudinal edge portions.

25 9. A system according to claim 8, characterized in that the platform is provided with nozzles extending along its longitudinal edge portions, and a fan supplying air under pressure to the nozzles, whereby to provide air curtains along either edge of the platform.

30 10. A system according to claim 8, characterized in that the fan is operative to extract air from the chamber above the platform and recirculate it to the nozzles.

35 11. A system according to claim 6 wherein in that the end members are each linked to the platform by a pin and slot arrangement, comprising a pin on the longitudinal roll axis of the platform, and a slot in the end member shaped to correspond to the locus of the said roll axis, the pin engaging the slot via means permitting movement of the platform relative to the track in a direction perpendicular to its plane.

40 12. A system according to claim 6, wherein the platform is provided with conformable edge seals, cooperating with the side walls of the track, and means controlled by relative movement of the platform and the end members are provided to regulate the pressure within the chamber in dependence upon the relative positions of the platform and the end members.

50 13. A system according to claim 12, wherein there is an air bleed aperture in a wall of the chamber provided with variable obturating means controlled by vertical movement of the platform.

55 14. A system according to claim 13, characterized in that the shape of the air bleed aperture is selected to provide the platform with a predetermined vertical suspension characteristic.

60 15. A system according to claim 13 wherein said pressure control means includes a fan for extracting air from said chamber, and said unobturated aperture is of a size permitting passage of sufficient air to prevent stalling of said fan.

65 16. A system according to claim 13 wherein the air bleed aperture is defined by a plate arranged for vertical movement in guides in said end members, and said aperture defining plate is connected to the support platform by means operative to lower the aperture de-

fining plate in response to inclination of the platform.

17. A system according to claim 12, wherein the conformable edge seals comprise a flexible seal member received in a slot in the edge of the wall being sealed, and biased towards the track surface by biasing means.

18. A system according to claim 17, wherein the biasing means is a chamber formed in the base of the slot and in communication with the atmosphere.

19. A system according to claim 17, wherein the biasing means are springs.

20. A system according to claim 17, including means directing pressurized fluid to the edges of the seal members adjacent to the track surface whereby to form fluid bearings.

21. A system according to claim 20, wherein wheels are positioned to provide auxiliary location of the wall or plate being sealed.

22. A system according to claim 6 wherein damping means are provided acting between the end members and the support platform.

23. A system according to claim 6, wherein means acting on the track independently of the support platform are provided to control roll of the support platform.

24. A system according to claim 6, wherein the platform is restrained against rolling movements by additional air cushion means connected to the platform and acting on the side wall of the track.

25. A system according to claim 24, wherein the additional air cushion means comprise, on each side of the vehicle, a row of longitudinally spaced means defining air cushions, said air cushion means being connected to the platform by a system of levers allowing the row of air cushion means to conform to curvature of the track wall.

26. A system according to claim 24, wherein the additional air cushion means comprise at least one further chamber defined on each side of the vehicle, by means of a central frame member supporting the platform, and seal plates slidably laterally relative to said frame member; said seal plates cooperating with said frame member, the end members and the side walls of the track to define said further chambers.

27. A system according to claim 26, wherein the seal plates also form the edge portions of the platform and define the chamber above the platform.

28. A system according to claim 26 wherein the position of the end members relative to the ends of the frame member determines the degree of obturation of passages placing the chambers defined above the platform and to either side of the frame member in communication with the atmosphere.

29. A system according to claim 25, wherein the passages communicate with the atmosphere through at least one further chamber within the support platform, the support platform carrying suction fans having inlets in communication with the several chambers defined above and to either side of the frame member, and outlets in communication with said further chamber.

30. A system according to claim 24, wherein the additional air cushion means comprise a separate guidance platform, the guidance platform cooperating with an additional vertically orientated channel section track portion to define an additional chamber, and wherein the additional track portion has top and bottom walls configured so that movement of the guidance platform, which is of fixed width, to either side of a predetermined lateral position results in gaps between the guidance platform and the top and bottom walls of the additional track portions becoming narrower, a fan unit being provided in communication with the additional chamber and adapted to selectively raise and lower the pressure therein relative to the atmosphere according to which side of said predetermined position the guidance platform lies.

31. A system according to claim 30, wherein the guidance platform cooperates with a surface on the underside of both the top and the bottom walls of the additional track portion.

32. A system according to claim 26, wherein the seal plates have conformable edge seals.

33. The system according to claim 32, wherein the conformable edge seals comprise a flexible seal member received in a slot in the edge of the wall being sealed, and biased towards the track surface by biasing means.
